UNITED STATES PATENT OFFICE.

CHRIS L. VOLZ, OF DETROIT, MICHIGAN.

RADIO RECEIVING CIRCUITS.

Application filed September 22, 1926. Serial No. 137,024.

This invention relates to radio receiving circuits and the object of the invention is to provide a radio receiving circuit arranged to produce the maximum power from each 5 stage of radio frequency amplification.

Another object of the invention is to provide a radio receiving circuit in which a condenser is connected across the secondary of each radio frequency transformer and adapted to feed back into the input of the previous 10 radio frequency stage.

Another object of the invention is to provide a radio receiving circuit in which the output of the radio frequency transformers 15 is divided, a portion of the current being fed into the input circuit of the preceding stage of radio frequency amplification.

A further object of the invention is to provide a means for balancing the radio 20 frequency stages so that more than the usual two stages of radio frequency amplification may be utilized with the same purity of reproduction and with the additional power attained by the extra stages.

These objects and the several novel features of the invention are hereinafter more 25 fully described and claimed and the preferred form of construction by which these objects are attained is shown in the accompanying drawings in which—

The figure is a schematic diagram of a radio receiving circuit embodying my invention.

As shown in the drawing a primary coil 35 1 of a radio frequency transformer is connected directly in the antennæ circuit. The secondary coil 2 is tuned by a variable condenser 3 and the input circuit 4 leads from the secondary coil 2 to the grid 5 of a vacuum tube 6. The output circuit 7 for the vacuum tube is connected to the plate 8 of the vacuum tube and leads to the primary coil 9 of the second radio frequency transformer. The secondary 40 10 of this transformer is tuned by the variable condenser 11. A three plate condenser 12 is connected across several of the turns of the secondary coil 10 and the central plate of this condenser is connected by means of a wire 13 to the input circuit 50 4 of the vacuum tube 6 as shown. The input circuit 14 for the vacuum tube 15 is connected at one end to the secondary coil 10 and at the opposite end to the grid 16 of the vacuum tube 15. The output circuit 17 for the vacuum tube 15 is connected to the plate 18 at one end and to the primary coil 19 of

the succeeding radio frequency transformer at the opposite end. The secondary coil 20 of this transformer is tuned by means of the variable condenser 21 and a three plate fixed 60 condenser 22 is connected across several of the turns of the secondary coil 20 as shown on the drawing. The central plate of the fixed condenser 22 is connected by means of a circuit 23 to the input circuit 14 of the vacuum tube 15. The input circuit 24 for the vacuum tube 25 is connected at one end to the secondary coil 20 and at the opposite end to the grid 26 of the vacuum tube 25. The output circuit 27 for this vacuum tube is connected at one end to the plate 28 and at the opposite end to the primary coil 29 of the next radio frequency transformer. The secondary coil 30 of this transformer is tuned by means of a variable condenser 31. A 75 three plate fixed condenser 32 is connected across several turns of the secondary coil 30 and the circuit 33 leads from the central plate of the condenser 32 to the input circuit 24 for the vacuum tube 25. This input circuit 34 for the vacuum tube 35 is connected to the secondary coil 30 and passes through the grid leak 36 to the grid 37 of this vacuum tube. The vacuum tube 35 is the detector tube and the plate 38 thereof may be 80 directly connected to a sound reproducing device 39 as shown or this output circuit may pass through an audio frequency amplifier before passing into the sound reproducing device. 85

The B battery 40 may be connected in the circuit as shown to supply plate voltage for the several vacuum tubes and the A battery 41 may be connected in the circuit as shown for lighting the filaments of the vacuum tube and rheostats 42 and 43 may be provided for controlling the filament voltages. 90

In this circuit the amount of feed back for a given frequency is arrived at by adjusting the three plate condensers 12, 22 and 32 and should correspond to the average tube 95 internal capacity. These condensers are of surplus capacity in construction and when mounted in the circuit they are set and fixed as above described. The number of secondary turns spanned by the tap leads from each of these condensers is 21 and the purpose is to create a variable feed back of varying frequency on the secondary and so cancel the grid to plate short circuiting condensive reactance. The outer plates of these 100 three plate condensers are shunted across 105

twenty-one turns of the secondary and in this circuit a variable reactance is set up by the winding and this outer plate condenser circuit is tapped by a center plate on which 5 a proper amount of current is collected for the feed back. In this circuit the phase relation of grid to plate capacity is opposed in the feed back and differs by one hundred and eighty degrees.

10 With this arrangement of balancing the circuit it is possible to use three stages of radio frequency amplification without distortion and with the clarity and faithfulness of reproduction of the usual two stages 15 of radio frequency amplification. By providing three stages of radio frequency amplification, together with this arrangement which prevents distortion, a very sensitive circuit is provided which is very efficient 20 in receiving over long distances.

From the foregoing description it becomes evident that the circuit is very simple and efficient in operation, is carefully balanced by means of the fixed condensers which feed 25 back into the input circuit of the previous stages and provides a device which accomplishes the objects described.

Having thus fully described my invention, its utility and mode of operation, what I 30 claim and desire to secure by Letters Patent of the United States is—

1. A radio receiving circuit comprising a

series of stages of radio frequency amplification, each stage including a vacuum tube and a radio frequency transformer connect- 35 ing the stages, a three-plate fixed condenser connected across several of the turns of the secondary of each radio frequency trans- 40 former, the central plate of each fixed con- denser being connected to the input circuit of the preceding stage.

2. A radio receiving circuit comprising a series of stages of transformer coupled radio frequency amplification, a three-plate con- 45 denser connected across several of the turns of each transformer secondary, the central plate of each condenser being connected to the input circuit of the preceding stage.

3. A radio receiving circuit comprising a series of stages of radio frequency amplifi- 50 cation each including a vacuum tube, a radio frequency transformer having a primary connected to the output circuit of one stage and a secondary connected to the input cir- 55 cuit of the succeeding stage, a three plate fixed condenser having the two outer plates connected across several of the turns of the secondary winding and a central plate connected to the input circuit of the preceding stage.

In testimony whereof I sign this specification.

CHRIS L. VOLZ.
